UNITED STATES PATENT OFFICE.

RÉNÉ EMILE DIOR, OF BILLANCOURT, FRANCE.

CONSTRUCTION OF SULPHURIC-ACID CHAMBERS.

1,426,261.

Specification of Letters Patent. Patented Aug. 15, 1922.

Application filed March 25, 1921. Serial No. 455,487.

To all whom it may concern:

Be it known that I, RÉNÉ EMILE DIOR, a French citizen, residing at Billancourt, Seine, France, have invented certain new and useful Improvements in the Construction of Sulphuric-Acid Chambers, of which the following is a specification.

This invention relates to improvements in the construction of chambers used in the manufacture of sulphuric acid.

It consists in forming the chambers of inverted funnel shape tapering throughout, the inclination of the sides of the upper part being more nearly vertical than that of the lower part. The invention further consists in making each chamber of the series decreasing in height to compensate for the diminution of the gaseous volume by the cooling of the gas and by the condensation producing sulphuric acid, the tallest chamber being connected to the Glover tower and the shortest one being connected to the Gay-Lussac tower.

The invention will be described with reference to the accompanying drawings.

Fig. 1 is a diagrammatic elevation of a series of four chambers constructed in accordance with the invention.

Fig. 2 is an elevation (to an enlarged scale) of a chamber constructed in accordance with the invention and showing means for supplying cooling water to the outside walls.

Fig. 3 is a plan of same.

Fig. 4 is a vertical section through the top of a chamber showing arrangement for supplying sulphuric acid thereto.

Fig. 5 is a vertical section through the top of another form of chamber showing arrangement for supplying sulphuric acid thereto.

Fig. 6 is a vertical section through the top of a chamber showing a further arrangement for supplying sulphuric acid adjacent to the inner walls thereof.

In carrying out the invention it is found that four chambers A' A² A³ A⁴ as shown in Fig. 1 are a suitable number to employ, and each chamber is formed of two frusto-conical portions a a', the sides of the lower portion a' being of greater inclination to the vertical than those of the upper portion a so that each chamber is of approximately the shape of an inverted funnel. The sides of each chamber are soldered to a base a² or the bottom edges may be immersed in an

acid bath so as to form a hydraulic seal. A tube B open at both ends, may pass vertically through the chamber as shown in Figs. 2 and 4, to damp or control the eddies set up by the walls of the chamber and by the condensation formed due to the cooling. The tube B may be replaced by any other means suitable for the purpose such as a jet of steam, atomized water or suitable diluted sulphuric acid injected at the top of the chamber along its vertical axis. Such a jet should be as long as possible and must not meet the walls of the chamber otherwise the lead of which the chamber is composed might be attacked.

As shown in Figs. 4, 5 and 6 an annular groove c is formed in the top of the chamber to receive an inverted cap C with toothed edges to allow a continuous pouring of sulphuric acid of 53° B. or other suitable concentration along the entire inner surface of the chamber.

The device may be replaced by or employed with a rotary re-acting turbine D as shown in Fig. 6 which will spread the liquid on to the inner surface of the walls of the chamber or any other suitable device may be employed for this purpose.

Injectors e for atomized water or diluted sulphuric acid may be arranged either on the cap as shown in Fig. 5, or in the walls of the chamber as shown in Fig. 6, the jets being directed downwards.

Where sulphuric acid is employed in the injector the jets can be directed towards the walls but in the case of water the jets must be directed towards the vertical axis of the chamber so that the water will not come into contact with the walls and attack the lead.

The outer surface of the chamber is cooled by allowing the water to flow down the outside of the walls as shown in Fig. 2 from a similar receptacle F formed at the upper part of the chamber A either through apertures at the groove or over a weir at the edge of the groove, the water being collected near the bottom by a second annular receptacle F'.

Where the chamber A is provided with an inner tube B the inner walls of the pipe may also be cooled by allowing a stream of water to flow down them.

Each chamber is provided with an outlet pipe g arranged near the top of the chamber and with an inlet pipe g' arranged near the

bottom. The pipes g and g' are arranged tangentially to the walls of the chamber so that the gas will be forced or circulate spirally or in the form of a screw against the 5 walls of the chamber.

In a battery of four chambers A' A^2 A^3 A^4 as shown in Fig. 1 the chambers are arranged side by side the inlet g' at the bottom of the first chamber A' being connected 10 to the Glover tower and the outlet g at the top of the first chamber to the inlet g' at the bottom of the second chamber A^2 and so on, the outlet g from the top of the last chamber being connected to the Gay-Lussac 15 tower. Each chamber is smaller in height than the preceding one to compensate for the diminution of the volume of the gas.

Although a battery of four chambers is shown in Fig. 1 any other convenient number 20 can be employed.

As will be seen from the diagram shown in Fig. 1 the diluted acid produced in chambers A^2 A^3 and A^4 is concentrated by being led back to supply the preceding chambers 25 and the acid formed in chambers A^3 and A^4 is de-nitrated by some of the concentrated acid formed in chamber A' being supplied thereto. This arrangement relieves the working of the Glover and Gay-Lussac 30 towers and assists in the recovery of the nitrous compounds.

The principles on which the apparatus is designed are as follows:—

1. The amount of sulphuric acid produced 35 is a function of the surface of the chambers in contact with the re-acting gases and varying with the temperatures of the surface.

2. Sulphuric acid H_2SO_4 is produced on 40 the inner cooled surface by the contact and rubbing of the gas with diluted sulphuric acid already produced and flowing down the walls. The flowing of the diluted sulphuric acid can be artificially increased by the introduction of previously prepared sulphuric 45 acid suitably diluted to about 53° Baumé. The introduction of previously prepared diluted sulphuric acid cools the gas circulating spirally or in the form of a screw against the walls separately or in combination with 50 the cooling of the walls by a stream of water flowing down their outer surfaces.

3. The introduction of the whole or part 55 of the necessary water for carrying out the re-action at the point where such reactions take place, i. e., at the walls and to intensify the reaction.

4. The concentration of the diluted acid produced in the second, third and fourth chambers and the denitration of the acid 60 formed in the third and fourth chambers, so relieving the working of the Glover and Gay-Lussac towers and assisting in the recovery of the nitrous compounds.

The decreasing section of the outlet of the 65 present chambers allows the gas in the

chamber to be carried off as soon as the output of acid which can be produced therein has been reached. The diminution of the reaction towards the top of the chamber is however much smaller than in the chamber 70 as previously constructed partly on account of the method of cooling and partly because the water and acid introduced into the chamber circulate in the opposite direction to the gas, the gas passing from bottom to 75 top in contact with the walls and the water and acid from top to bottom.

About 60 per cent of the acid produced is obtained from the first chamber and 40 per cent from the second chamber the third and 80 fourth chambers being employed to finish the reaction and recover as much as possible of the nitrous acid before passing to the Gay-Lussac tower. To achieve this it is necessary to accurately regulate the quantity 85 and strength of the steam or atomized water and acid in the third and fourth chambers. Fans or pumps are employed for including a draught to force the gases through the 90 chambers.

What I claim as my invention and desire to protect by Letters Patent is:—

1. A chamber for use in the manufacture 95 of sulphuric acid formed of two frusto-conical portions disposed in upright position and the one portion superposed on and connected to the remaining lower portion, the sides of the lower portion being of greater inclination to the vertical than the sides of the upper portion and the upper portion of the chamber forming a contracted enclosing area, an inlet connection to the lower portion of the chamber, and an outlet connection to the upper portion of the chamber.

2. A series of chambers for use in the 105 manufacture of sulphuric acid each composed of two frusto-conical portions and having the side wall of the lower portion of greater inclination to the vertical than the side wall of the upper portion, each chamber decreasing in height regularly throughout the series of chambers to compensate for the diminution of the gaseous volume by the cooling of the gas and by the condensation producing the sulphuric acid.

3. A chamber for use in the manufacture 110 of sulphuric acid formed of two frusto-conical portions of different dimensions, the surrounding side wall of the lower portion being of greater inclination to the vertical than the side wall of the upper portion and the latter portion having a greater vertical extent than the lower portion, and inlet and outlet pipes arranged respectively tangentially to the enclosing side wall of the lower 115 and upper portions of the chamber to cause the gas to circulate spirally against the walls of the chamber.

4. A chamber for use in the manufacture 120 of sulphuric acid formed of two frusto-

conical portions differing in diametrical and vertical dimensions, the side wall of the lower portion being of greater inclination to the vertical than the side wall of the upper portion, a vertical tube passing through the center of the chamber fully from the lower terminal of the lower portion to within a short distance of the top of the upper portion to damp or control the eddies set up 10 by the walls of the chamber and by the condensation of the gases.

5. A chamber for use in the manufacture of sulphuric acid formed of two frustoconical portions differing in diametrical and 15 vertical extent and having the side wall of the lower portion of greater inclination to the vertical than the side wall of the upper portion, and means associated with the

chamber to damp or control the eddies set up by the walls of the chamber and by the condensation of the gases. 20

6. A chamber for use in the manufacture of sulphuric acid formed of two frustoconical portions differing in diametrical and vertical extent and having the side wall of the lower portion, which is of greater diameter, of greater inclination to the vertical than the side wall of the upper portion, and means on the outer portion of the walls of the chamber for causing a stream of water 25 to be supplied to and flow thereover to cool the complete chamber wall. 30

In testimony whereof I have hereunto set my hand.

RÉNÉ EMILE DIOR.
